(57) **CLAIM**

The ornamental design for a firearm trigger, as shown and described.

DESCRIPTION

FIG. 1 is a right-front angled view of the firearm trigger, showing the new design.

FIG. 2 is a front view thereof.

FIG. 3 is a back view thereof.

FIG. 4 is a right-side view thereof.

FIG. 5 is a left-side view thereof.

FIG. 6 is a top view thereof; and,

FIG. 7 is a bottom view thereof.

The broken lines in the figures depict unclaimed portions of the firearm trigger only and form no part of the claimed design.
